UNITED STATES PATENT OFFICE.

WILLIS KENT, OF MEAFORD, ONTARIO, CANADA.

WOOD-SPLITTING MACHINE.

1,150,038.

Specification of Letters Patent. Patented Aug. 17, 1915.

Application filed October 1, 1912, Serial No. 723,305. Renewed February 19, 1915. Serial No. 9,418.

To all whom it may concern:

Be it known that I, WILLIS KENT, of the town of Meaford, in the county of Grey, in the Province of Ontario, Canada, have invented certain new and useful Improvements in Wood-Splitting Machines, of which the following is the specification.

The object of the invention is to devise a machine particularly adapted for splitting cord wood into longitudinal quarter sections and consists essentially of a suitable base designed to hold the cord wood from lateral movement, a vertical splitting wedge designed to split the wood vertically, an adjustable horizontal splitting wedge located immediately behind the vertical wedge, and means for driving the cord wood longitudinally against the vertical and horizontal splitting wedges as hereinafter more particularly explained by the following specification.

Figure 1, is a perspective view of my device. Fig. 2, is a side elevation. Fig. 3, is a sectional elevation. Fig. 4, is an end elevation. Fig. 5, is a sectional detail of the splitting wedges.

In the drawings like letters of reference indicate corresponding parts in each figure.

A' and A² are standard castings, suitably supported on a base B, having a holding trough B' V-shaped in cross section into which the wood is fed. The castings A' and A² are connected together at the top by a longitudinal guide rod B² and at the bottom by longitudinal guide rods B³ and B⁴.

C is a hammer provided with sleeve bearings C', C² and C³ slidably mounted upon the guide rods B², B³ and B⁴.

D, is a cylinder provided with a piston D' and piston rod D², extending through the end casting A' forming one end of the cylinder. The outer end of the piston rod D², is threaded or otherwise suitably secured in the hammer C.

D³ are suitable operating valves and ducts designed to convey suitable motive fluid into the cylinder to reciprocate the piston D' longitudinally.

A⁴ is a guide piece secured to a casting A⁸ by a suitable bolt A⁹.

A⁵ is the wedge portion of the casting A² having vertical guides A¹⁵ in which it is slidably held against the guide piece A⁴.

A⁶ is a hardened steel cutting edge secured with the wedge block A⁵ by suitable tap screws A⁷.

A¹⁸ is a pulley journaled on a suitable standard A¹⁹ forming an extension of the casting A².

A¹⁰ is a horizontal bearing forming part 60 of the casting A'.

A¹¹ is a pull bar provided with a series of notches A¹², designed to co-act with the projection A¹³ formed in the guide-way A¹⁰.

A¹⁴ is a cable extending from the pull bar A¹¹ around the pulley A¹⁸ to the casting A⁸ to which it is suitably secured.

A²⁰ and A²¹ are cutting wedges formed of hardened steel secured by tap screws A²² and A²³ to the casting A⁸ so as to form 70 horizontal cutting edges. It will be understood that the casting A⁸ is freely held upon the bolt A⁹ so as to turn thereon.

In operation a piece of cord wood rests in the V-shaped holding groove B', between the hammer C and the cutting wedges A⁵, A²⁰ and A²¹. When the hammer C is driven

against the end of the piece of cord wood by means of the piston and piston rod D' and D² respectively the opposite end of the 80 piece of cord wood is carried first against the cutting edge A⁶ which splits the cord wood vertically.

After such vertical split has been started the end of the cord wood is brought against the cutting wedges A²⁰ and 85 A²¹ so as to split the vertically split portions horizontally. By repeated blows at the hammer C, the piece of cord wood is split

into four quarters from end to end. Should the grain of the wood be twisted the horizontal cutting wedges A²⁰ and A²¹ will swing 90

around the bolt A⁹ so as to follow such twist in the grain and thereby prevent any possibility of the cutting wedges becoming jammed.

By pulling the pull bar A¹¹ longitudinally the horizontal cutting wedges A²⁰ and A²¹ may be adjusted vertically according to the variations in diameter of the different pieces of cord wood thus insuring the splitting of each piece centrally at each 100 operation.

In order to cushion the blow of the hammer C at each end of the stroke I have provided cushion springs H, H¹, H², H³, H⁴, and H⁵.

What I claim as my invention is:

1. In a cord wood splitting machine, the combination with a suitable base having means for holding the cord wood stick in position, of a vertical stationary splitting 110 wedge and a vertically movable horizontal splitting wedge located at one end of the

- stick and a splitting hammer located at the opposite end of the stick, and means for operating the hammer against the stick, as and for the purpose specified.
5. In a cord wood splitting machine, the combination with a suitable base having means for holding the cord wood stick in position, of vertical and horizontal splitting wedges located at one end of the stick, said 10 horizontal wedge being capable of vertical movement, and a splitting hammer located at the opposite end of the stick and means for operating the hammer against the stick, as and for the purpose specified.
15. 3. In a cord wood splitting machine, the combination with a suitable base having means for holding the cord wood stick in position, of a vertical stationary splitting wedge located at one end of the stick, a 20 splitting hammer located at the opposite end of the stick, means for operating the hammer against the stick, and a vertically movable horizontal cutting wedge located to the rear of the vertical cutting wedge, as and for the purpose specified.
25. 4. In a cord wood splitting machine, the combination with a suitable base having means for holding the cord wood stick in position, of a vertical stationary splitting wedge located at one end of the stick and a 30 splitting hammer located at the opposite end of the stick, and means for operating the hammer against the stick, a horizontal cutting wedge located to the rear of the vertical cutting wedge and pivotally supported 35 behind the vertical cutting wedge so as to tilt in a vertical plane, as and for the purpose specified.
40. 5. In a cord wood splitting machine, the combination with a suitable base, having means for holding the cord wood stick in position, of a vertical stationary splitting

wedge located at one end of the stick and a splitting hammer located at the opposite end of the stick, and means for operating the hammer against the stick, a horizontal cutting wedge located in the rear of the vertical cutting wedge, and means for adjusting the horizontal cutting wedge vertically, as and for the purpose specified.

45. 6. In a cord wood splitting machine, the combination with a reciprocating hammer, of a vertical cutting wedge, a base casting for the cutting wedge having a vertical guide-way, a horizontal cutting wedge slidably supported in the guide-way, and means for adjusting the horizontal cutting wedge vertically, as and for the purpose specified.

50. 7. In a cord wood splitting machine, the combination with a reciprocating hammer, of a vertical cutting wedge, a base casting for the cutting wedge, a swivel bolt mounted upon the base casting, and a horizontal cutting wedge pivoted centrally on the swivel bolt, as and for the purpose specified.

55. 8. In a cord wood splitting machine, the combination with a reciprocating hammer, of a vertical cutting wedge, a base casting for the cutting wedge having a vertical guide-way, a horizontal cutting wedge slidably supported in the guide-way, a notched pull bar held in a horizontal bearing adapted to coact with the notches of the pull bar to adjust the longitudinal position of the pull bar, a suitably mounted pulley, a cable 60 extending from the pull bar around the pulley to the horizontal cutting wedge to which it is attached, as and for the purpose specified.

65. WILLIS KENT.
